UNITED STATES PATENT OFFICE

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed May 24, 1924. Serial No. 715,645.

The invention relates to draft rigging for railway cars and more particularly to improvements in the means for connecting a coupler to the cushioning elements, and to 5 the means whereby the strains incident to draft and buffing are transmitted to the car underframe.

To this end, the principal object of my invention, generally considered, is to provide 10 a yoke member which may be formed of cast steel, the arms of the yoke being so located that the cushioning mechanism is open to inspection and may be removed from the car underframe without the removal of the 15 yoke or coupler.

A further object of the invention is to provide a hooded horizontal yoke adapted to be connected to the coupler by means of a vertically extending key whereby the coupler 20 may have both horizontal and vertical swinging movements independent of the yoke without imparting destructive strains thereto.

A still further object of the invention is to 25 provide in connection with the horizontally disposed yoke a key-connected front follower and a combined backstop and tie casting, said key and backstop forming a support and guide for the yoke and being adapted to 30 maintain the yoke in proper position independent of the cushioning mechanism.

To these and other ends, the invention consists in the various elements and combinations of elements as hereinafter set 35 forth, the novel features being pointed out in the claims.

Referring now to the drawings:

Figure 1 is a view partially in plan and partially in section of a car underframe 40 showing the invention applied thereto.

Figure 2 is a longitudinal vertical section of the construction shown in Figure 1.

Figure 3 is a horizontal sectional view of the forward end portion of the yoke and associated parts shown in Figure 2.

Figure 4 is a similar view through the backstop and tie casting of Figure 2.

Throughout the several figures like parts are designated by like reference characters.

50 The numeral 1 designates a combined striking casting and coupler carry iron which may be of any desired form, 2 the end sill, and 3 the center or draft sills of a car underframe. 4 is the coupler which is provided in its shank with a longitudinally ex-

tending vertically arranged slot 5 and which also may be provided with a transversely arranged slot 6.

Each of the sills 3 is provided with a longitudinally extending slot 7 and connected to the outer face of each sill, preferably by a plurality of rivets, is a slotted cheek plate or stop casting 8 having a boss 9 adapted to extend within the slot 7 of the adjacent sill, the said boss surrounding a longitudinally extending slot 10 formed in each cheek plate. The boss 9 preferably forms an inward continuation of a flange 11 which is formed on the outer face of each cheek plate, the flanges 11 and bosses 9 at the opposite ends of each slot forming extended bearing surfaces 12 to engage the correspondingly formed faces of a transversely extending follower connecting key 13.

At a suitable distance from the cheek plates 8 the sills 3 are connected by a combined tie, backstop and preferably center casting 14, the said casting having a vertically extending interrupted stop face 15 formed by flanges 16 and 17, said flanges 16 and 17 having formed on their adjacent edges and preferably integral therewith, rearwardly extending webs or flanges 18 and 19, respectively, the object and purpose of which will hereinafter be described. Said casting 14 when employed as a center casting is provided with a hollow thimble 20 and is also formed with a plurality of stiffening webs and flanges 21, 22 and 23. Longitudinally extending webs or flanges 24 form the side walls of the casting and are suitably apertured so as to receive the rivets 25, by means of which the stop and tie casting is rigidly connected to the adjacent portions of the underframe.

Extending rearwardly from the coupler and forming the means by which the same is connected to the cushioning mechanism 26 (which is diagrammatically shown by the dot and dash lines 27) is a yoke 28 comprising a pair of arms 29 connected adjacent the stop casting 14 by an integral portion 30. At its forward end, there is connected to and preferably integral with the arms of the yoke, transversely extending plates 31 which, in conjunction with the adjacent portions of the arms 29, form a hooded or box-like end portion 32 into which the slotted portion of the coupler shank 4 is adapted to extend. Each of the plates 31 is provided with a lon-

itudinally extending slot 33, portions of which slots coincide with the slot 5 in the coupler shank. The coupler is preferably connected to the yoke by means of a vertically extending key 34, said key being adapted to extend through the aligned slots 33 and 5 in the yoke and coupler, respectively, and is normally positioned in engagement with the forward ends of the slots 33 and the inner end of the slot 5. The slots 33 preferably are of greater width than the slot 5 so that the coupler may pivot or swing horizontally independently of the yoke on the forward edge of the key 34 as a pivot. The key 34 may be retained in position by any suitable means as for example by providing on the lower plate 31 a pair of spaced perforated ears 35 and extending through the perforations a bolt or other suitable means 36. The key 34 may, if desired, be provided with a head 37 which is adapted to rest upon the bolt 36.

From a point substantially adjacent the rear edge of the key 34 when the same is in normal position, the adjacent faces of the plates 31 are flared upwardly and outwardly, as clearly shown at 38. This construction not only permits a slight vertical angling of the coupler shank 4 so as to permit the necessary movement thereof when the car is passing over a hump, as for example in classification yards or in car dumping inclines, without detrimental strains upon the yoke, but also provides clearance for the forward end of a box follower 39 which is slotted, as at 40, so as to receive and be supported by the key 13.

The portion 30 of the yoke 28 is normally adapted to rest upon the web 19. That is, the portion 30 of the yoke extends within the recess in the wall 18 of the stop casting and lies between the webs 18 and 19, and since the over-all length of the portion 30 is slightly greater than the permissive movement of the cushioning mechanism, the yoke will always be maintained in engagement with the stop casting 14 and will be guided in its reciprocatory movements by the said webs or flanges 18 and 19.

To support the cushioning mechanism, there is provided the usual form of carry irons 41 and 42 which are connected to the lower flanges of the sills 3 by bolts 43 or other suitable fastening means. It will be understood of course that while I have illustrated a plurality of carry irons, that a single carry iron may be substituted if desired.

It will be observed that the rearward portions of the plates 31 overlie the forward portion of the follower 39 thereby effecting economy of space and, as illustrated on the drawings, also extend rearwardly of the adjacent ends of the slots 44 which are provided in each of the yoke arms 29, through which slots the end portions of the key 13

extends. This latter feature is a natural consequence of the former, as the slots 40, registering with slots 44, are nearly as long as the follower 39. It should also be noted that the arms 29 of the yoke are widened from a point in rear of the slots 44 so that the cross-sectional area of the arms is not diminished by the said slots.

Having now described my invention, what I claim is:

1. In a draft rigging for railway cars, the combination with center sills, of a yoke interposed between the same, the arms of said yoke being arranged parallel with the planes of the webs of said sills, and means for connecting the forward ends of said arms, said means comprising a pair of slotted plates having their adjacent faces rearwardly and outwardly inclined.

2. In a draft rigging for railway cars, the combination with slotted center sills, of a horizontally disposed slotted yoke interposed between the same, said yoke being formed with arms increased in width forwardly from points rearwardly of said slots, a follower within said yoke, a key passing through said yoke slots for connecting said follower and yoke, means for connecting the arms of said yoke adjacent the forward end thereof, said means comprising a pair of slotted plates, a coupler and means for connecting said coupler and yoke, said last named means comprising a vertically arranged key adapted to extend within the slots of said plates.

3. In a draft rigging for railway cars, the combination with the center sills, of a yoke comprising arms joined by slotted web portions forming a hooded end interposed therebetween, the arms of said yoke being disposed in planes parallel to the webs of said sills, a coupler, a vertically arranged key extending through the slots in said web portions for connecting said yoke and coupler, a follower positioned between the arms of the yoke with the forward portion thereof disposed between the said web portions, and means bridging said sills and disposed adjacent opposite ends of said yoke for slidably supporting the same in operative position.

4. In a draft rigging for railway cars, the combination with the center sills, of a hooded yoke interposed therebetween, the arms of said yoke being disposed in planes parallel to the webs of said sills, a follower within said yoke, a portion of said follower extending within the hooded portion of said yoke, a coupler normally engaging said follower, means for connecting said coupler and yoke, and means for connecting portions of said yoke arms above and below said coupler and in rear thereof.

5. A yoke for railway draft rigging, comprising a pair of slotted arms and slotted plates connecting said arms adjacent one

end thereof, the said plate slots being elongated and arranged in a plane at an angle to the plane of the longitudinal axes of the slots in said arms, portions of said plates 5 extending rearwardly of the adjacent ends of the slots in said yoke arms.

6. A yoke for railway draft rigging comprising a pair of arms each of which is provided with longitudinally extending slots 10 therein, and a pair of plates each of which is connected to an end portion of said arms, said plates and the adjacent portions of said arms being adapted to form the hooded end of said yoke, said plates having longitudinally extending slots therein, the longitudinal axes of said last named slots being arranged parallel with the vertical planes of said yoke arms, and portions of the adjacent faces of said plates being rearwardly inclined away from each other. 15

7. In a draft rigging for railway cars, the combination with the center sills, of a hood-

ed yoke interposed therebetween, the arms of said yoke being disposed in planes parallel to the webs of said sills, a coupler, the 25 hooded portion of said yoke being provided with longitudinally extending slots in the upper and lower portions thereof, and a vertically extending key for connecting said coupler and yoke, the slots in said yoke being adapted to permit pivotal movement of said coupler in a horizontal plane, the slotted walls of said yoke being formed with rearwardly outwardly inclined faces arranged above and below said coupler, for permitting 30 a vertical rocking movement of said coupler within said yoke for permitting a vertical rocking movement of said coupler within said hooded portion, said last named means comprising rearwardly outwardly inclined 35 faces arranged above and below said coupler.

In testimony whereof I affix my signature.
